UNITED STATES PATENT OFFICE.

EDGAR OLIVER BLEKRE, OF MINNEAPOLIS, MINNESOTA.

DESIGN FOR A VEHICLE-TIRE.

58,058.

Specification for Design.

Patented June 7, 1921.

Application filed December 15, 1920. Serial No. 430,974. Term of patent 7 years.

To all whom it may concern:

Be it known that I, EDGAR OLIVER BLEKRE, a citizen of the United States, residing at Minneapolis, in the county of Hennepin and State of Minnesota, have invented a new, original, and ornamental Design for Vehicle-Tires, of which the following is a specification, reference being had to the accompanying drawings, forming part thereof.

Figure 1 is a plan view of a portion of a vehicle tire, showing my new design and Fig. 2 is a fragmentary sectional view taken on the line 2—2 of Fig. 1.

I claim:

The ornamental design for a vehicle tire, as shown.

EDGAR OLIVER BLEKRE.
